UNITED STATES PATENT OFFICE

NILE OLDHAM, OF CHICAGO, ILLINOIS, ASSIGNOR TO CHICAGO ROLL SCREEN COMPANY,
OF CHICAGO, ILLINOIS, A CORPORATION OF ILLINOIS

ROLL SCREEN GUIDE

Application filed May 3, 1926. Serial No. 106,278.

This invention relates to a new and improved roll screen construction, and more particularly to a construction for supporting the edges of roll screens. In my co-pending application, Serial Number 98,963, filed April 1, 1926, I have disclosed a roll screen and roll screen edge supporting construction comprising members projecting from the window frame or wall adjacent the window. 10 The present construction is a modified form by means of which the edges of the screen are supported within the contour of the adjacent frame or wall structure.

It is an object of the present invention to 15 provide a new and improved construction for supporting the edges of roll screens, and more particularly to such a construction adapted to be located substantially within the supporting wall contour.

20 It is a further object to provide a construction of this character in which the edge engaging means is loosely supported from the member secured to the wall, so that it may remain in the proper relation to the screen 25 regardless of variations in the wall.

It is an additional object to provide a construction of this character which is simple in design and adapted for commercial production.

20 Other and further objects will appear as the description proceeds.

I have illustrated a preferred embodiment of my invention in the accompanying drawings, in which

35 Figure 1 is a horizontal section through one side of a window with the invention applied thereto;

Figure 2 is an enlarged fragmentary section showing a portion of Figure 1; and

40 Figure 3 is a vertical section taken on line 4-4 of Figure 2.

Referring first to Figure 1, the metallic window frame member 68 is secured in place in the masonry surrounding the window, and any desired form of window may be provided. The edge of the screen 34, as shown in Figure 2, is provided with members 46 which may be staples or similar elements secured to the edge of the screen fabric.

50 These members maintain the edges of the

screen in the tubular chamber 73 formed by the track members 74.

The lower edge of the screen 34 is provided with a clip 53 which has secured to its ends the members 54 having a reduced portion 55 extending between the jaws of the members 74, and the tubular portion 57 extending within these members. The spring catch 58 is adapted to spring over the lower portion of the clip 53 to retain the screen in the lower position.

The supporting members 75 are secured to the face of the window frame or adjacent wall by means of screws 76. In the form shown in Figure 2 these screws are driven into the wooden window frame 77. In the form shown in Figure 1, the screws fasten into the strips 78 which are let into the plaster 71. The members 75 are provided with the gripping flanges 79 which carry the loose rivets 80. The guide members 74 are provided with flanges 81 extending between the flanges 79 and these flanges are provided with elongated openings 82, adapted to receive the loose rivets.

The form of screen guiding construction shown is adapted for application to walls in such a manner as to be contained within the wall contour. The edge of the screen is firmly gripped and a complete insect proof closure is afforded. The loose rivets passing through the slots in the guide members permit these members to remain parallel even though the supporting wall surface may be slightly warped or irregular. These slots also permit the use of the support without the necessity for careful adjustment of the support within small fractions of an inch, so as to properly receive the guiding extensions 57 on the bottom clip of the screen. It will be apparent that by the provision of approximately half an inch play in the slots of the supports on either side of the window, a total variation of an inch is allowed which is ample to take up any variation in window width, as well as variation in screen width due to necessary tolerances in manufacture.

While I have illustrated one preferred form of my invention it is to be understood that I contemplate such changes and modi-

fications as come within the spirit and scope of the appended claims.

I claim:

1. Edge supporting means for a screen, comprising a pair of longitudinally extending supporting members having inturned portions forming a recess, and edge gripping track means extending longitudinally of the recess.
10. 2. Edge supporting means for a screen, comprising a pair of longitudinally extending supporting members having inturned portions forming a recess, and edge gripping means extending longitudinally of the recess, said means being loosely secured to the supporting members in such manner as to permit a limited relative movement.
15. 3. Edge supporting means for a screen, comprising a pair of longitudinally extending supporting members having inturned portions forming a recess, and securing portions beyond the recess, and edge gripping means extending longitudinally of the recess, said means having a portion extending 25 between the securing portions of the supporting members.
20. 4. Edge supporting means for a screen, comprising a pair of longitudinally extending supporting members having inturned portions forming a recess, and edge gripping means comprising a pair of elements having inwardly faced concave grooves forming a longitudinally extending track for the edge of a screen, said means being located within 25 the recess formed by the supporting members.
25. 5. Edge supporting means for a screen, comprising a pair of longitudinal extending supporting members having inturned portions forming a recess, and edge gripping means comprising a pair of elements having inwardly faced concave grooves forming a longitudinally extending track for the edge of a screen or the like, said means being located within the recess formed by the supporting members, and loosely secured to the supporting members in such manner as to permit limited relative movement.
30. 6. Edge supporting means for a screen, comprising a pair of longitudinally extending supporting members having inturned portions forming a recess, and securing portions beyond the recess, and edge gripping means extending longitudinally of the recess, said means having a portion extending between the securing portions of the supporting members, and loose rivets extending through the securing portions and the portion of the gripping means.
35. 7. Edge supporting means for a screen, comprising a pair of longitudinally extending supporting members having inturned portions forming a recess, and edge gripping means extending longitudinally of the recess, said gripping means being secured to the

supporting members by means of loose rivets extending through laterally elongated slots whereby a limited lateral movement is permitted the gripping means relative to the supporting members.

Signed at Chicago, Illinois, this 20th day of April, 1926.

NILE OLDHAM.
